UNITED STATES PATENT OFFICE.

CHARLEY D. AGEE, OF DALLAS, TEXAS.

CABINET IRONING BOARD.

Application filed October 17, 1922. Serial No. 595,043.

To all whom it may concern:

Be it known that I, CHARLEY D. AGEE, a citizen of the United States, residing at Dallas, in the county of Dallas and State of

5 Texas, have invented certain new and useful Improvements in Cabinet Ironing Boards, of which the following is a specification. This invention relates to new and useful improvements in cabinet ironing boards.

10 The object of the invention is to provide a cabinet having a pair of superposed doors operatively connected to an ironing board in such a manner as to be raised into a closed position when the board is pushed down into the cabinet, and lowered into a parallel position when the cabinet is opened and the board extended.

A further object is to arrange the doors so that the upper one travels faster than 20 the lower door, whereby the doors are brought to a parallel position when fully open and to a superposed position when fully closed. Another object is to connect the board with the sliding doors in such a 25 manner as to cause it to move in harmony therewith.

A still further object of the invention is to provide spring means for aiding in raising the board from its horizontal position 30 and also in cushioning its downward movement. Another object is to provide means for taking up the slack in the flexible connections.

35 A construction designed to carry out the invention will be hereinafter described together with other features of the invention.

The invention will be more readily understood from a reading of the following specification and by reference to the accompanying drawings, in which an example 40 of the invention is shown and wherein:

Fig. 1 is a vertical sectional view of a cabinet constructed in accordance with my invention and showing the same open and 45 the ironing board extended,

Fig. 2 is a similar view showing the cabinet closed,

Fig. 3 is an enlarged cross-sectional view 50 on the line 3—3 of Fig. 1,

Fig. 4 is an enlarged detail of one of the upper chain pulleys,

Fig. 5 is an enlarged detail of one of the door raising pulleys and component parts,

55 Fig. 6 is a front elevation of the cabinet in its closed position, a portion of the lower

front being omitted to show interior construction,

Fig. 7 is a similar view of the cabinet in its open position, the upper portion being omitted,

Fig. 8 is a detail of one of the ironing board slides, and

Fig. 9 is an enlarged detail showing one of the hinge mountings of the board.

In the drawings the numeral 10 designates an upright casing or compartment rectangular in cross-section and provided with a facing frame 11 at its front side. The lower portion of the frame is closed by a panel 12 above which is disposed a transverse apron 13 supporting a transverse sill 14 above which the frame is open. The sill projects outwardly and is braced by brackets 15.

On each side of the casing is mounted vertical guide strips or members 16 and 17, respectively, which are spaced apart to provide opposite vertical channels or guideways 18. The strips 16 are disposed against the rear wall of the casing, while the strips 17 have their front edges substantially flush with the rear sides of the frame 11 which is offset laterally as is best shown in Fig. 3, to form a front vertical channel or guideway 19. A finishing frame 20 mounted on the frame 11 and extending upwardly from the sill 14 overhangs the channel 19. The guide strip 17 has a widened section 17' at its upper end on each side, the rear edge of each being flush with the rear edge of the strip and the front edge extending into the channel 19.

An upper door 21 and a lower door 22 are arranged to slide in the channels 19 and these doors are placed one in front of the other, their combined thickness being such as to permit an easy sliding in said channels. To the upper edge of each side of the upper door 21 is attached one end of a chain or other flexible connection 23. These chains pass up the channels 19 and each is received in a vertical groove 17^a in the front edge of the correlated section 17'. In the upper portion of each section 17' is journaled a pulley 24 as is shown in detail in Fig. 4 and over which the chain passes. From the pulley each chain passes down a groove 17^b in the rear edge of each strip 17 and its section 17'.

In each channel or guideway 18 is disposed a short slide or carrier 25, which is

shown in detail in Fig. 8. Each carrier has a small pulley 26 journaled in its lower end and projecting into the groove 17^c from which it receives the chain 23. In the rear 5 edge of each carrier is provided a vertical groove 25' up thru which the chain passes from the pulley. A cross bar 27 is mounted in the guideways and has eye bolts 28 extending therethru and receiving the ends 10 of the chains. Wing nuts 29 are mounted on the bolts on top of the bar and by tightening said nuts the slack in the chains is taken up. It will be seen that the chains are looped over the pulleys 24 and under the 15 pulleys 26 and when the upper door 21 is raised the carriers are lowered by reason of the loops of the chains lengthening, below the pulley 24.

An ironing board 30 is hinged to the carriers at its inner end. Angular trunnion-bolts 31 have their lateral extensions fulcrumed in the carriers and their vertical portions extending thru the board which is fastened thereon by nuts 32 engaging the 20 upper and lower faces of said board. By adjusting the nuts the board is adjusted with relation to its pivot points. For holding the trunnion-bolts in place metal brackets 33 are fastened to the side edges of the board and 25 provided with slots thru which the lateral portions of the bolts pass. In order to assist in the raising of the board from a horizontal position and to cushion the end of the downward swing, a harp spring 34 is coiled about 30 the lateral extension of each bolt. Each spring has one leg fastened to the carrier, as by a staple 35 and the other leg fastened to the board, as by a keeper 36. The springs are arranged so that when the board is 35 folded as in Fig. 2, the tension is practically relieved, but when the board is extended and swung down to its operative position the springs are opened and placed under tension.

40 When the board is extended its rear side portions engage under stop blocks 37 projecting from the rear strips 16, while said board rests upon the sill 14 and is thus firmly supported in position,

45 When the doors are open as is shown in Fig. 1 the doors 21 and 22 are parallel, the upper doors standing directly in front of the lower, but when the doors are raised to close the cabinet, the upper door is above the 50 lower door. To accomplish this the upper door must move faster than the lower door during the closing operation. A cross bar 38 is mounted on the front side of the lower door under the upper door, the lower door 55 being slightly longer. At each side of the lower door small pulleys 39 are housed in the door and bar and project rearwardly into a vertical groove 17^c in the strip 17. The pulleys 26 and 39 projecting into the grooves 60 65 as described, act as guides. Small cords or

other flexible connections 40 are suitably fastened at one end to lower side edges of the upper door and pass under the pulleys 39 to the grooves 17^c. These cords pass up 70 said grooves and thru holes in the strips 17 to eye bolts 28' having wing nuts 29' like the bolts 28 and being adjustable to take up the slack in said cords.

Finger notches 21' or equivalents are provided in the opposite ends of the door 21. 75 When the cabinet is closed the ironing board 30 occupies an upright position between the guideways 18 and the channels 19. In the upper portion of the casing a shelf 41 for holding an iron or other articles is provided 80 and the front edge of this shelf is concaved as is shown at 42. When the board is raised its upper reduced end will pass thru the concaved portion and by contacting with the edge will be guided outwardly.

85 With the doors closed as is shown in Fig. 2, to open the cabinet the fingers are placed in the notch 21' at the top of the upper door 21 which is pulled downward. When the door 21 begins to move downward the loops of the cord 40 in which the pulleys 39 are supported begin to lower and as these loops support the lower door it will be lowered at the same time. However as the 90 chains are double-looped and the cords only single looped the upper door will travel faster than the lower and when the doors are fully lowered the upper door will stand in front of the lower door. This is due to the fact that the lower door is dependent 95 upon the elongation of the cord loops, whereas owing to the double looping of the chains and the single strands of the chains hanging from the pulleys 24 the upper door is permitted to gain upon the lower door.

100 As the doors descend the carriers are elevated by the chains and the ironing board 30 carried upwardly, its upper end being pushed outwardly by the concaved edge 42. The board swings outwardly over the upper 105 edge of the upper door and as it approaches its horizontal position the springs 34 are brought under tension and act as cushions to some extent. The board is arrested in a horizontal position by engagement with the 110 stop blocks 37 and the sill 14.

To return the board to the cabinet and close the same the board is swung upwardly, in which the springs assist, whereby the carriers are started downwardly and the doors 115 raised above the sill. After the board has been swung into the casing, the closing operation may be completed by moving the door 21 upwardly.

120 I have shown a metal pocket 43 set into the rear or inner end of the board and shaped to receive an iron (not shown). The iron may be laid upon its side in said pocket and being on the inner side of the pivots of the board, will aid in lifting the board from 125 130

its horizontal position. But it is to be expressly understood that said pocket may be omitted or any other kind of weight substituted or used in any convenient place.

5 Various changes in the size and arrangement of the various parts as well as modifications may be made within the scope of the appended claims.

What I claim, is:

10 1. In an ironing board cabinet, a casing having a horizontal support at the front, an ironing board movably mounted therein, a sliding door, a flexible looped connection secured at one end to the casing above said support and at its opposite end to the door, and bearings upon the inner end of the board and the upper portion of the casing for the oppositely looped portions of said connection, whereby the board and door are operated conjointly.

15 2. In an ironing board cabinet, a casing having a horizontal support at the front, an ironing board pivotally and slidably mounted therein, a sliding door, a flexible looped connection secured at one end to the casing above said support and at its opposite end to the upper portion of the door, bearings upon the inner end of the board and upper portion of the casing for the oppositely looped portions of said connection arranged to raise and unfold the board outwardly when the door is opened, and a spring element connected to the board at its pivot and tensioned in such unfolding movement to compensate for the weight of the board and assist in returning the board to its enclosed position.

20 3. In an ironing board cabinet, a casing, an ironing board slideable and foldable into the casing, a pair of sliding doors for closing the cabinet, a pair of double looped flexible connections attached to the casing and the upper door, the ironing board being supported in one of the loops, bearings upon said board and casing for the loops of the connections and a pair of single looped flexible connections attached to the casing and the upper door, the lower door being supported in the loops of the single connections.

25 4. In an ironing board cabinet, a casing hav-

ing opposed guideways and opposed channels, carriers slideable in the guideways, upper and lower doors, slideable in the channels, an ironing board pivoted to the carriers, pulleys on the carriers and at the upper end of the casing, a pair of flexible connections attached at one end to the casing and at the other end to the upper door, the intermediate portions of said connections being looped around the said pulleys, and a second pair of flexible connections attached at one end to the casing and at the other end to the upper door and looped around pulleys on the lower door.

30 5. In an ironing board cabinet, a casing, an ironing board slideable in the casing, a pair of slideable doors, and means attached to said casing and connected with said doors and said board for sliding said doors into parallel relation at the bottom of the casing and elevating the lower end of the board, whereby said board may be swung out over said doors.

35 6. In an ironing board cabinet, a casing, an ironing board slideable in the casing, a pair of vertically slideable doors in superposed relation, a pair of double looped flexible connections having one end stationary in the cabinet and supporting the board in one of the loops and attached to one of the doors, pulleys in the cabinet supporting the other loop, a pair of single looped flexible connections having one end stationary in the cabinet and supporting the other one of the doors in its loop and attached to the first mentioned door.

40 7. In an ironing board cabinet, a casing, an ironing board slideable and foldable into the casing, a pair of doors slideable upon each other for closing the casing, a double looped flexible connection attached to the casing and upper door, bearings upon said board and casing for the loops of said connection, a single loop flexible connection attached to the casing and the upper door, and a bearing upon the lower door supported in the loop of said single connection.

45 In testimony whereof I affix my signature.

CHARLEY D. AGEE.
